UNITED STATES PATENT OFFICE.

ALLEN E. OSTRANDER, OF RIDGEWOOD, NEW JERSEY, ASSIGNOR TO AMERICAN R
AND FOUNDRY COMPANY, OF ST. LOUIS, MISSOURI, A CORPORATION OF N. Y.
JERSEY.

TANK-CAR ANCHOR.

1,122,413.

Specification of Letters Patent. Patented Dec. 29, 1914.

Application filed December 16, 1912. Serial No. 737,141.

To all whom it may concern:

Be it known that I, ALLEN E. OSTRANDER, residing at Ridgewood, Bergen county, New Jersey, and being a citizen of the United States, have invented certain new and useful Improvements in Tank-Car Anchors, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1 is a central, vertical, longitudinal, sectional view taken through the end portion of a tank and an underframe equipped with the present invention, Fig. 2 is a plan view of the anchor forming the subject-matter of the present invention with the tank removed, and showing the parts of a car underframe in the near vicinity of the anchor. Fig. 3 is a vertical, longitudinal sectional view of the invention, the section being taken on line 3-3 of Fig. 2.

It is well known that tank cars used for transporting fluid products comprise, generally, an underframe with a tank suitably mounted thereon and held in position between end head blocks or by an anchorage of some suitable type and the tank is held in position on the underframe by conventional tank bands which partly surround the tank and are anchored to the underframe. Owing to the nature of the lading it is found quite difficult to anchor the tank in position in such manner as to prevent some slight longitudinal shifting, which shifting is considered a disadvantage.

To overcome difficulties heretofore encountered the present invention comprises an anchoring means adapted to anchor the tank of a tank car to its underframe in such manner as to prevent longitudinal shifting of the tank, the tank and tank anchoring parts being so disposed as to permit free removal of the tank from its underframe when required without removing the wedging means employed to hold the tank in po-

sition on its supporting underframe and, when it is desired to so separate the tank from said underframe, this may be readily accomplished without destructive effort.

Referring to the parts: 1 is a fragment of a carbody or tank of the conventional form provided with longitudinally extending bottom sheet 2 and mounted above the underframe, comprising center sills 3-3 with bolster 4. By preference an anchor is provided depending from near each end of the tank and is shown as positioned forwardly of the bolster 4 and relatively between such bolster and the ends of the center sills; that is, between the bolsters and the couplers, (latter not shown).

In the embodiment of the invention disclosed in the drawings lugs or stops 6 are attached to the center sills 3, as shown in Figs. 1 and 2, said lugs comprising a bolster filling casting spanning the space between the center sills and including the bolster filler 5 are riveted to the sills and form connections for the center sills. Depending from the tank is the anchor casting 7, which, as shown in Fig. 1, is provided with an arcuate top flange 8, conforming to the curvature of the bottom sheet 2 of the tank and is riveted securely thereto. The anchor casting comprises spaced walls extending longitudinally between the sills 3.

It will be noted that the face 9 of the anchor 7 is slightly inclined. Interposed between the stop lugs 6 and the legs of the anchor 7 are two-part wedges 10 and 11, which wedges are perforated vertically for the passage therethrough of a supporting bolt 12, which preferably has its head at the upper side and adjusting nuts 13 and locking nuts at its lower side. As shown in Figs. 1 and 3, the faces of the lugs 6 in proximity to the inclined face 9 of the anchor are oppositely inclined and are serrated as best shown in Fig. 3, the serrations comprising relatively fine teeth. The wedges 10 and 11 are likewise serrated on their faces which contact with the serrated portion of the lugs 6, and it is to be noted that the wedge 10 is provided with a relatively small orifice 15, the purpose of which will be hereinafter described.

The lugs 6 may be formed integral with the bolster filler 5, as best shown in Figs. 1

and 2, or may comprise a separate casting held in position by bolts or rivets passing through said lugs and through the center sills, as may be desired. The parts of the car may be assembled with the anchor attached to the tank, after which the tank may be placed in position and the wedges drawn together by pressure of the adjusting nut 13. The preferred manner of assembling 10 the parts is to rivet the bolster center filler 5 with its integral lugs 6 in position between the center sills, support the upper wedge 10 in position by a pin passing through the orifice 15 of sufficient length to span the gap 15 between the center sills, thereby supporting the wedge 10 in position with the bolt 12 held in position in the upper wedge, after which the tank may be placed in position, the pin referred to withdrawn from the orifice 15, whereupon the wedge 10 will fall by gravity to a position between the lugs 6 and the anchor 7, after which the wedge 11 may be placed in position on the bolt. When this 25 is done the nut 11 is screwed on to the lower end of the bolt, thereby bearing against the lower face of the lower wedge 11, and causing the head of the bolt to bear against the upper face of the upper wedge 10, in consequence of which, as said nut 13 advances on 30 the bolt, the wedges 10 and 11 will be drawn together, thereby filling the gap 16 between the lugs 6 and anchor 7. It is evident that the wedges on each side of the longitudinal center of the underframe may be separately 35 adjusted to compensate for any irregularity of spacing of the lugs 6 and next adjacent faces of the anchor 7. The serrations 17 in the opposing faces of the lugs 6 and the wedges 10 and 11 are oppositely disposed; that is, the serrations at the upper 40 portion of the face of the lug 6 open downwardly and the serrations at the lower portion of the lugs 6 open upwardly, while the serrations in the wedges 10 and 11 are oppositely disposed.

It is evident that in a structure subjected 45 to the vibratory stresses incident to operation of a tank car that the wedge 10 will settle or become automatically positioned in a lower plane during the operation of the car, at which time the upwardly open serrations on the lower face of the lug 6 will hold the lower wedge 11 in position, so that the upper wedge 10 will automatically adjust itself during shifting longitudinally of the tank on its underframe. While there 55 may be an advantage in placing the wedges near both ends of the underframe, it is evident that but one set of said wedges is necessary, as the operation of the upper wedge is automatic and will readily compensate for any increase in distance between the anchor 7 and its contiguous lug 6.

By using the wedges in connection with 60 the anchor for the tank, it is obvious that

the tank may be more firmly locked in position against movement longitudinally of its supporting underframe. It is well known that tanks of tank cars are heavy bodies which are ordinarily lifted by means of power cranes, and extreme care must be taken in placing the tanks in position under normal conditions, in addition to which some clearance between the anchor 7 and the stop lugs is required to facilitate placement of 75 the tank, which clearance, even though small, sometimes permits independent movement of the tank on the underframe.

When the wedges 10 and 11, or a single wedge 10 is used, as before described, it is 80 evident that the tank may be placed in position with the wedge 10 in position, after which the wedge 10 will automatically adjust itself so as to fill the gap 16. Another advantage in the use of the two wedges is 85 that the tank is more securely held in position above the bolsters, so that rocking of the tank on its underframe is prevented.

While the wedges 10 and 11 are held in position in operation the tank will be held 90 by friction of such wedges against the face 9, so as to prevent separation of the tank and underframe under normal conditions, though it is obvious that there will be no positive interlocking of the wedges with the 95 face 9 of the anchor which will prevent separation in the event of a wreck tipping the car off the track, in which latter case such separation is desirable to facilitate replacement.

What I claim is:—

1. In a tank anchor for tank cars, the combination of a fixed abutment and a juxtaposed vertically movable anchor, said abutment having a face inclined in two directions, and a vertically movable interposed wedge.

2. In a tank anchor for tank cars, the combination of a fixed abutment and a juxtaposed vertically movable anchor, each of said members having an inclined face, and a plurality of vertically movable interposed wedges having faces on one side inclined in opposite directions.

3. In an anchorage device for the tanks 115 of tank cars, an abutment in the plane of the car underframe, an anchor depending from the tank, a plurality of vertically movable spaced wedges interposed between said anchor and abutment, and means for 120 lessening the space between said wedges.

4. In an anchorage device for the tanks of tank cars, a fixed abutment and a removable anchor, each provided with inclined faces, and a plurality of oppositely inclined 125 adjustable wedges adapted to engage therewith.

5. In an anchorage device for tanks of tank cars, an underframe comprising spaced sills, a bolster-filler spacing the sills of said 130

underframe, an anchor member depending from the tank, and a wedge interposed between said bolster filler and anchor member.

6. In an anchorage device for tanks of tank cars, a two-part vertically movable wedge, and means for actuating said wedge.

7. In an anchorage device for tanks of tank cars, a two-part vertically movable wedge, and means for actuating and locking said wedge.

8. In a tank anchorage device, a vertically movable two-part wedge, and means adapted to engage therewith.

9. In a tank anchorage device, a vertically movable two-part wedge, and means adapted to engage and interlock therewith.

10. In a tank car, a tank, a support therefor, and a gravity actuated wedge-shaped anchoring device locking the tank in position on said support.

11. In a tank car, a combination comprising a gravity operable tank anchoring wedge.

12. The combination with spaced center sills having a plurality of spaced apart stops carried therebetween, of a tank having an anchor attached thereto and depending therefrom between said center sills and in alignment with said stops, and a plurality of independently and vertically movable locking means disposed between the stops and one side of the anchor.

13. As a means for anchoring a tank on a car underframe, transversely spaced apart vertically movable wedges each disposed between a depending element attached to the tank, and a portion of the underframe horizontally disposed relative to the element attached to said tank.

14. The combination with an underframe, including center sills, lugs carried by said sills, a car body, an anchor member depending from said body between said center sills, and a plurality of transversely spaced apart vertically movable members filling the space between said lugs and said anchor.

15. The combination with an underframe, of a car body carried thereby and removable therefrom without destructive effort, a plurality of transversely spaced wedges within said underframe locking said car body to said underframe, and means for moving said wedges vertically independently of each other.

16. In a car, center sills, a plurality of spaced stops carried between said sills, an anchor spanning the distance transversely between said stops, and a plurality of transversely spaced wedges disposed between said stops and the anchor at one side of said anchor.

17. In a tank anchor for tank cars, the combination of a freely removable tank, a fixed abutment, and a juxtaposed vertically movable tank anchor co-operating with said

abutment, each of said members having an inclined face, and a vertically movable interposed wedge.

18. In a tank anchor for tank cars, the combination of a freely removable tank, a fixed abutment and a juxtaposed vertically movable tank anchor co-operating with said abutment, one of said members having an inclined face, and a plurality of vertically movable interposed wedges adapted to move toward each other.

19. In a tank anchor for tank cars, the combination of center sills, a freely removable tank, a fixed abutment connected to said sills, and a juxtaposed vertically movable tank anchor co-operating with said abutment, said anchor having an inclined face, and a vertically movable interposed wedge.

20. In an anchorage device for the tanks of tank cars, a freely removable tank, an abutment in the plane of the car underframe, an anchor depending from the tank adapted to coact with said abutment, and a plurality of vertically movable wedges interposed between said anchor and abutment.

21. In an anchorage device for the tanks of tank cars, center sills, a freely removable tank, a fixed abutment secured to said sills, a tank anchor provided with an inclined face, and a vertically movable locking wedge interposed between said abutment and said anchor.

22. In an anchorage device for the tanks of tank cars, a fixed abutment and a removable tank, an anchor for said tank provided with an inclined face, and a plurality of oppositely and vertically movable interlocking wedges.

23. In an anchorage device for tanks of tank cars, a freely removable tank, an underframe including sills, a bolster-filler spacing the sills of said underframe, a member depending from the tank, and a vertically movable wedge adapted to fill the space between said bolster-filler and said member.

24. In a tank car, a freely removable tank, a support therefor, and a gravity wedge-shaped anchoring device locking the tank against longitudinal movement on said support.

25. As a means for anchoring a tank in position on an underframe of a tank car, a member depending from the tank below the top plane of the underframe, a fixed element of the underframe, and a plurality of wedges interposed between one side of said depending member and said fixed element.

26. As a means for anchoring a tank in position on an underframe of a tank car, a member depending from the tank below the top plane of the underframe, a fixed element of the underframe, and a wedge interposed between said depending member and said

fixed element adapted to fill the gap between said member and element when the car is in service, and to permit removal of the tank without removal of said wedge.

- 5 27. As a means for anchoring a tank of a tank car to an underframe, transversely spaced independently and vertically movable wedges, each disposed between a vertical element attached to the tank and a por-

tion of the underframe which is in horizontal alignment with a part of said vertical element.

In witness whereof I have hereunto set my hand in the presence of two witnesses.

ALLEN E. OSTRANDER.
